UNITED STATES PATENT OFFICE.

ERNEST B. THURSTON, OF TOLEDO, OHIO, ASSIGNOR TO THE HAUGHTON ELEVATOR & MACHINE COMPANY, OF TOLEDO, OHIO, A CORPORATION OF OHIO.

ELEVATOR CONTROL.

Application filed July 31, 1926. Serial No. 126,197.

This invention relates to the control of electric hoisting machinery for elevators and similar apparatus.

The general object of the invention is to provide a control whereby, when the operator has started the elevator in the desired direction of travel, the starting switch may be returned to its off or neutral position, and the elevator will continue in that direction of movement, until stopped automatically at the terminal, without further attention from the operator.

A further object of the invention is to provide means, independent of the starting means, whereby during the automatic travel of the elevator, the operator can stop it at any selected intermediate landing. The running of the elevator therefore requires no attention, after it is once started, unless it is desired to stop at an intermediate floor, and the operator is thus left free to guard the passengers and watch his signals.

In the drawings, Figure 1 is an across-the-line diagram of the wiring for a push-button control elevator showing wirings and connections for a three-phase single speed motor without acceleration, each intermediate floor being provided with two floor-control switches one for the up-circuit and one for the down-circuit, all such switches being located in the operating circuits; Fig. 2 is a similar diagram of the operating circuit, showing a single floor control switch for each intermediate floor; Fig. 3 is a similar diagram of the operating circuit, the floor control switches for the intermediate floors being located in the holding circuit; Fig. 4 is a similar diagram of both power and operating circuits, the operating circuit differing from the one shown in Fig. 3 in that the switch that initiates stopping is magnetically opened through the pushing of the stopping button by the operator; Fig. 5 is similar to Fig. 4, except that it shows a magnet-controlled stopping switch for each intermediate floor instead of a single magnet-controlled stopping switch for all intermediate floors; Fig. 6 is an across-the-line diagram similar to Fig. 4, except that a sliding contact switch is substituted for push-button control; Fig. 7 shows a modification of the sliding switch control shown in Fig. 6, and Fig. 8 is a diagram of both power and operating circuits similar to those shown in Fig. 5, but showing primary windings for a two-speed motor and also

showing accelerating resistances for both speeds.

In the interest of simplicity, the invention is illustrated in all but Figure 8 with a three-phase single speed alternating current squirrel cage induction motor, without the usual acceleration. Anyone familiar with the art may add or use, when desired, any known method of acceleration or may substitute any other phase motor or a direct current motor in place of the alternating current motor, without departing from the spirit of my invention.

The main elevator controller for the single speed alternating current motor is shown as composed of the two usual direction magnet switches. A main line or a potential magnet switch may be used, if desired, although not shown.

The power circuits are shown in heavy lines and the switch-control circuits by light lines. In all the figures, A represents a power motor, B a magnet switch coil for the up circuit, C a magnet switch coil for the down circuit, D an up direction starting switch, E a down direction starting switch, F a stopping switch, G safety devices, H cams for opening floor-stop switches, and J a brake magnet coil. The power supply lines are indicated as L¹, L² and L³.

The switch frames operated by coils B and C are mechanically interlocked so that when one of them is in operating position the other must be in inoperative position, thus insuring against short circuits.

The safety devices G may be any of the standard safeties required for any particular installation, such as overtravel limits, safety or overspeed governor switch, door switches, emergency switch, etc.

The floor controller may be a unit in the machine room designed (as shown in the drawings) with the cam element H moving to the right when the elevator travels up and to the left when the elevator travels down, and so arranged that it will open the contacts in a definite relation to the respective floors; or it may be switches located in the hatchway, and opened by a cam on the car; or it may be a switch or switches on the car opened by cams at the floors.

A brake is provided, and may be of any type that will be magnetically released by the energizing of coil J, and may be either spring or gravity set.

105

110

Referring to Fig. 1, only the primary windings of the motor A are shown, the secondary windings being omitted. Power line L³ is permanently connected by conductor 1 to phase X of the motor windings, and lines L¹ and L² are connected respectively to phases Y and Z for driving the motor in the up-direction, and are reversely connected for driving it in the down-direction.

10 For the up-direction, power line L¹ is connected through lines 2 and 3 to phase Y of the motor windings, and power line L² is connected through lines 4 and 5 to phase Z of the motor windings. For the down direction, power line L¹ is connected through lines 6 and 5 to phase Z of the motor windings and power line L² is connected through lines 7 and 3 to phase Y of the motor windings.

15 The up direction control circuit comprises line 8, leading from line L¹ to coil B, and lines 9 and 10, leading from coil B to line L². The down direction control circuit comprises line 11 leading from line L¹ to coil C, and lines 12 and 10, leading from coil C to line L².

20 A normally open push button switch D is interposed in line 8, and a by pass or shunt circuit 13 leads around switch D through holding switch 14. In line 11 there is a similar push button switch E with a by pass or shunt circuit 15 and holding switch 16.

25 In circuit 8, between switch D and coil B, there are intermediate floor switches 17 and 18 and a limit switch 19 for the top floor.

30 The construction shown is for a four story installation. If there are more or less floors, the only change necessary is in the number of switches for intermediate floors. Intermediate floor switches 17 and 18 are closed except when opened by cam H, and there is a by pass or shunt line 20 leading around these intermediate switches.

35 In circuit 11 there is a limit switch 21 for the bottom floor and floor switches 22 and 23 for the intermediate floors, and a by pass or shunt circuit 24 leading around intermediate switches 22 and 23.

40 A normally closed double pole push button switch F is interposed in circuits 20 and 24.

45 Safety devices G are interposed in line 10, common to both the up and down control circuits, and the coil J of the brake is in a line 27 connecting lines 3 and 5, so that the coil is energized whenever power is applied to the motor in either direction.

50 Safety interlock normally closed switches 28 and 29 are interposed in lines 9 and 12 respectively.

55 Normally open switches 30, 31, 32 and 33 are interposed in lines 2, 4, 6 and 7 respectively.

60 Means 34, actuated by the energization of coil B, operates to close normally open holding switch 14, open safety interlock switch 29, and close power switches 30 and 31. Simi-

larly, means 35 actuated by coil C operates to open safety switch 28 and to close holding switch 16 and power line switches 32 and 33.

65 The operation of the device will be clear from the above description, but will be briefly described for convenience in understanding the invention.

70 If push button E is operated to close line 11, coil C is energized, switches 32 and 33 are closed to complete the down direction power circuits, and the car starts down. At the same time, safety switch 28 is opened, so as to prevent closing of the up direction control circuit, and holding switch 16 is closed, so that the car continues its downward movement after button E is released. If the operator does nothing further, the car continues to the bottom floor, where limit switch 21 is opened, which results in deenergizing coil C and allowing power switches 32 and 33 to open and stop the car. At the same time, holding switch 16 is opened and safety switch 28 is closed.

75 If the operator desires to stop at the second floor, he pushes button F, opening shunt circuit 24, and, when cam H opens, switch 22, coil C is deenergized, switches 16, 32 and 33 opened, switch 28 closed, and the car stopped. It will be noted that, when thus stopped at an intermediate floor, the car may be started in either direction. Button F performs its function if pushed simultaneously with D or E, or at any time thereafter before the desired floor is reached.

80 When it is desired to start the car in the up direction, either from the third floor position shown or from any lower floor, push button D is closed. This energizes coil B, closing switches 14, 30 and 31 and opening switch 29, thus starting the car, insuring the continuance of the motion after the push button is released, and preventing the closing of the down circuit before the opening of the up circuit. In the absence of further action on the part of the operator, the car continues its upward movement until it reaches the top floor, when limit switch 19 is opened, coil B is de-energized, the car is stopped, and the control switches are returned to starting position.

85 If the car is started from a floor lower than the next to the top, it may be stopped at any intermediate floor by opening circuit 20 by means of push button F and holding it open until the intermediate floor switch is opened by cam H, whereupon coil B is de-energized and the car stopped.

90 It will be readily seen that coil J is energized whenever current is supplied to the motor in either direction, thus releasing the brake when power is applied, and that the coil is de-energized and the brake applied whenever power is shut off from the motor. Also since safety devices G are in a line common to both the up and down control circuits, 95

they operate to stop the car in either direction of travel. The arrangement shown in Fig. 2 is similar to that shown in Fig. 1, and corresponding parts are designated by the same reference characters, except the modified line in which safety devices G are placed.

In Fig. 2, the intermediate floor switches are omitted from lines 8 and 11, and instead switches 36 and 37, for the 2nd and 3rd floors respectively, are interposed in line 10^a, corresponding to line 10 in Fig. 1, and common to both the up and down control circuits. A by pass or shunt circuit 38 connects line 10^a on opposite sides of switches 36 and 37, and has switch F interposed therein.

The installation shown in Fig. 2 operates in exactly the same way as that shown in Fig. 1, except that, by the interposition of the intermediate floor switches in a line common to both the up and down control circuits, one switch for each floor and a single pole switch F are sufficient to control the car at the intermediate floors in either direction. It will be obvious that the same result may be obtained by interposing this intermediate floor switch arrangement in any line common to the two control circuits.

The installation shown in Fig. 3 is similar to that shown in Figs. 1 and 2, and the same reference characters are used to designate the different parts except those which are modified.

In Fig. 3, as well as in Fig. 2, the intermediate floor switches are omitted from lines 8 and 11. In Fig. 3 the intermediate floor switches are placed in holding lines 13^a and 15^a, corresponding to lines 13 and 15 in Fig. 1.

In line 13^a there are second floor switch 39 and 3rd floor switch 40, by passed by a line 41, while in line 15^a there are similar floor switches 42 and 43 by passed by line 44. A double push button switch F controls lines 41 and 44. The operation of this installation is identical with that shown in Fig. 1, the only difference being in the location of the switches.

Fig. 4 is similar to Figs. 1 and 3 as to most features, and the same reference numerals are used except as to the modified part of the arrangement. In Fig. 4, lines 13^b and 15^b are constructed similarly to lines 13^a and 15^a in Fig. 3, except that holding lines 41^a and 44^a, with holding switches 45 and 46, respectively, are substituted for by pass lines 41 and 44.

A line 47 is provided connecting power lines 6 and 7 between their respective switches and the motor. This line has a portion divided into parallel lines 48 and 49. Floor control switch is placed in branch 48. Line 47 passes through a coil F C that, when energized, actuates mechanism 50 which closes a holding switch 51 in branch 49 and opens switches 45 and 46 in lines 41 and 44.

In this construction, line 27^a of brake coil

J is shown attached to lines 6 and 7 instead of to lines 3 and 5. It will be understood that it is immaterial at what points either brake circuit 27^a or line 47 is attached to the two portions of the power circuits connected to phases Y and Z respectively and between the motor and the power switches.

The operation of the installation shown in Fig. 4 is similar to that described in connection with Fig. 1, except for the method of stopping at intermediate floors. When switch F in line 48 is closed, coil F C is energized and switch 51 is closed and holds the circuit through coil F C until power is switched off of the motor. As long as coil F C is energized, switches 45 and 46 remain open. It follows that, when button F has been pushed, it may be immediately released and the by pass circuits 41^a and 44^a will remain open, so that the first opening of a floor switch by cam H cuts out the current from control coil B or C, as the case may be, and stops the car. When power is cut off from the motor, coil F C is de-energized, switch 51 is allowed to open and switches 45 and 46 are allowed to close. Thereafter the car may be operated in either direction past intermediate floors until button F is pushed once more.

It will be seen that, in this installation, the only attention required of the operator is to push the starting button and thereafter, if a stop is to be made at an intermediate floor, push button F after passing the adjacent floor, so that the operator has both hands free at the time the car stops.

The installation shown in Fig. 5 is similar to that shown in Fig. 4, and the same reference characters are used for all except the modified parts.

The control circuits 8 and 11 and their connections are the same in Fig. 5 as in Fig. 4 except as to the by pass lines around the floor switches. In Fig. 5, there are separate by pass lines 41^b and 41^c around switches 39 and 40 respectively, and separate by pass lines 44^b and 44^c around switches 42 and 43 respectively. Normally closed switches 52, 53, 54 and 55 are interposed in the lines by passing switches 39, 40, 42 and 43 respectively.

Control line 47^a is shown connected to power lines 6 and 7, as in Fig. 4. It is separated for a distance into parallel lines 56 and 57. One end of line 56 passes through coil F C^a, while the other end is separated into parallel lines 58 and 59. A normally open push button switch F^a controls line 58, while a normally open holding switch 60 is interposed in line 59.

Similarly, line 57 passes through a coil F C^b, and is separated into lines 61 and 62, which are in parallel. A push button switch F^b controls line 61 and a holding switch 63 is interposed in line 62.

The operation of the installation shown in Fig. 5 is the same as that shown in the pre-

viously described figures except for stopping at intermediate floors. When the car is in motion and the operator wishes to make a stop at the second floor, for example, the 5 switches having been previously set for some other floor, he pushes in button F^2 , energizing coil F^C^2 . This coil actuates means 64 which operates to close holding switch 60 and thereby maintain the circuit through the coil 10 until the car is stopped.

Means 64 also operates to open switches 52 and 54, so that, whenever either switch 39 or switch 42 is opened by the floor control cam H, control coil B or C, as the case may be, is 15 de-energized, and the car is stopped. It will be noted that button F^2 can be released immediately after coil F^C^2 is energized, as holding switch 60 maintains the circuit until the required operation has been performed. 20 Furthermore, it will be noted that, if button F^2 is pushed immediately after the car is started down, the car will continue past floor three to floor two, as switches 53 and 55 in bypass lines 41^c and 44^c about the third floor 25 control switches 40 and 43, remain closed, not being affected by push button F^2 .

Similarly, if button F^3 is pushed with the car in motion towards the third floor, coil F^C^3 is energized, and through means 65 closes 30 holding switch 63 and opens bypass switches 53 and 55, whereby the push button may be released immediately, and the car will be stopped when switch 40 or 43, as the case may be, is opened by the floor control cam H.

35 This installation is slightly more complicated than that shown in Fig. 4, but has the advantage that pushing the appropriate button selects the desired floor for the next stop, at any time after the car has started, regardless of whether or not there is an intervening floor, whereas the installation shown in Fig. 4 requires that the operator shall push the button after all intervening floors have been passed, as the stop is made at the next 45 floor after the button is pushed.

The installation shown in Fig. 6 is similar in effect to that shown in Fig. 4, and the corresponding parts are designated by the same characters. Fig. 6 differs from Fig. 4 chiefly by showing a sliding or rotary type of switch in place of push buttons, and by showing the intermediate floor control circuit in parallel with the other control circuits instead of directly connected to the power circuit. 50

55 Sliding or rotary bar K is adapted to make connection between power line L^1 and contact D^7 at the end of line 8, contact E^7 at the end of line 11, or contact F^a or F^b , described later.

The floor control coil F^C is in control 60 line 66 connected at one end to line 10 and having its other end separated into branches 67 and 68 connected to terminals F^a and F^b respectively. A normally open holding switch 69 is interposed in branch 67 and is operatively connected to means 35 so that it is

closed when coil C is energized. A similar holding switch 70 in branch 68 holds a similar relation to coil B.

A normally open holding switch 71 is closed by the energizing of coil F^C , which also 70 opens switches 45 and 46, as in Fig. 4. A line 72 runs from branch 67 to switch 71 and a line 73 runs from branch 68 to switch 71. Closing switch 71 connects lines 72 and 73 with a line 74 leading to power line L^1 . 75

Supposing the operator wishes to start up with an installation like that shown in Fig. 6, bar K is moved upward. Connection is first made between the power line and terminal F^a , but, as switches 69 and 71 are both 80 open, no current passes until the bar makes contact with terminal D^7 , whereupon current passes through coil B, starting the car and closing switches 14 and 70. After this, bar K may be moved back to neutral position and 85 the car will run until stopped by the terminal switch, unless the operator intervenes.

If the operator desires to stop the car at an intermediate floor, he moves the bar down to contact terminal F^b . As switch 70 is held 90 closed by coil B, this contact energizes coil F^C , closing holding switch 71 and opening bypass switches 45 and 46. Thereafter bar K may be moved back to neutral position and current will pass through switch 71, line 73 95 and switch 70 to coil F^C until cam H opens switch 39 or 40, whereupon coil B is de-energized, the car stopped, and the switches returned to the position in which they are shown in the drawing. 100

Downward movement is effected in like manner by moving bar K downward to make connection with contact E^7 , and then stoppage at an intermediate floor can be effected by moving bar K upward to make connection with contact F^a , the detailed operation being obvious from the above description of the up direction operation. 105

The installation shown in Fig. 7 operates in substantially the same way as that shown in Fig. 6, and the same reference characters are used for the same parts. The difference between the two installations is in the arrangement for stopping at intermediate floors. 110

In the installation shown in Fig. 7, holding switch 71^a, operated by coil F^C and corresponding to switch 71 in Fig. 6, is interposed in a line 74^a connecting line 67, between contact F^a and switch 69, with power line L^1 . Lines 67 and 68 are connected, adjacent contacts F^a and F^b , by a line 75. 115

In operation, after the car has started, bar K may be moved to contact F^a or F^b . Because of connection 75, a circuit will be completed through whichever of switches 69 and 70 is closed and through coil F^C , which closes holding switch 71^a and opens switches 45 and 46, so that the car is stopped at the next floor when cam H opens the respective 120

125

130

floor switch. It will be seen that the operation is the same as with the installation shown in Fig. 6, except that stoppage may be made at any floor in either direction by moving bar K either way. It will be obvious also that switches 69 and 70 might be reversed without affecting the operation, and that either contact F^a or F^b could be omitted and the other used always. By locating switches 69 and 70 in portions of the circuit of coil F C which are in parallel, but one circuit is needed, as it operates in the same way, whichever switch, 69 or 70, is closed.

Fig. 8 shows an installation somewhat similar to that shown in Fig. 5 with the addition of provisions for multi-speed operation.

In the construction shown in Fig. 8, there is a low speed motor A¹ and a high speed motor A². These motors are three phase motors similar to that indicated in the other figures, except that they are shown with starting resistance. In the installation shown, the resistance coils R¹, R², R³, R⁴, R⁵ and R⁶ are introduced in the Y of motor A¹, and similarly resistances R⁷, R⁸, R⁹, R¹⁰, R¹¹ and R¹² are introduced in the Y of motor A². Switches 76, 77, 78 and 79 are arranged to cut out the resistance in motor A¹ and switches 80, 81, 82 and 83 are arranged to cut out the resistances in motor A².

The motors are energized by an arrangement of lines similar to that shown in the other figures. The lines 2, 4, 6 and 7 with their switches 30, 31, 32 and 33 are identical with those shown in the other figures, and are given the same reference numerals. Line 3^a is similar to line 3 in the other figures, except that it is connected to the phase Y¹ of motor A¹ and the phase Y² of motor A², instead of being connected to but one motor. Line 5^a, corresponding to line 5 in the other figure, is connected to phases Z¹ of motor A¹ and Z² of motor A² in a manner which will be described later.

Connected to phases Y¹ and Z¹ of motor A¹ there is a line including a coil M which controls the resistance. Means 84 which is operated when coil M is energized, operates to first close switches 76 and 77, thereby cutting out resistances R¹, R² and R³. Thereafter in control timed sequence connected means 84^a closes switches 78 and 79, thereby cutting out resistances R⁴, R⁵ and R⁶.

In a similar manner a coil N is energized by a connection between phases Y² and Z² of motor A². Means 85 operated by the energizing of coil N first closes switches 80 and 81 to cut out resistances R⁷, R⁸, and R⁹, and then by connected means 85^a closes switches 82 and 83 to cut out resistances R¹⁰, R¹¹ and R¹².

Phase X¹ of motor A¹ is connected to power line L⁸ by a line 86. A line 87 similarly connects power line L⁸ to phase X² of motor A².

A line 88 connects phase Z¹ of motor A¹ to line 5^a, and line 89 connects phase Z² of motor A² to line 5^a. Normally closed switches 90 and 92 are interposed in lines 86 and 88 respectively, and normally opened switches 91 and 93 are interposed in lines 87 and 89 respectively. The means for controlling the up and down circuits, and for controlling the various floor switches is the same as shown in Fig. 5 and is designated by the same reference characters, with the addition of means for automatically regulating the connections to the two motors.

A line 94 is provided connecting power line L¹ to line 10 through a coil LC. Coil LC actuates means 95 which operates to open switches 90 and 92 and to close switches 91 and 93.

A line 96 connects power line L¹ to line 94 between line L¹ and coil LC. A switch 97 is interposed in line 94, and is normally opened until closed by the energizing of coil B. A similar switch 98 is interposed in line 96 and is normally open until closed by the energizing of coil C. In the construction shown, one push button D^a operates a normally opened switch in both lines 8 and 94, and a similar push button E^a controls lines 11 and 96.

An intermediate floor switch control system and terminal switches, similar to those connected with lines 8 and 11, are connected to lines 94 and 96 respectively, and are designated by the same reference numerals with the addition of the letter l.

The installation shown in Fig. 8 is operable in the following manner, which will be seen to be substantially the same as the operation of the installation shown in Fig. 5, with the addition of the resistance and multi-speed features.

When the car is to be started in the up direction, push button D^a is actuated to close lines 8 and 94. This energizes coil B at once, closing switches 30 and 31 and energizing motor A¹. When motor A¹ is energized, coil M is energized, and through suitably timed mechanism cuts out the resistance. The timing of this mechanism may be controlled by dash pots or any other well known timing devices.

The energizing of coil B also closes switch 97. A suitable timing mechanism may be inserted, so that the closing of switch 97 will follow the energizing of coil B after the selected interval. When switch 97 is closed, coil LC is energized, thereby opening switches 90 and 92 and closing switches 91 and 93. This cuts out motor A¹ and energizes motor A². If desired, the timing mechanism may be omitted between coil B and switch 97, and inserted between coil LC and switches 90, 91, 92 and 93. The latter arrangement is preferable in some respects, as it enables the immediate release of push button D^a without waiting for

the energizing of the high speed motor. It will be understood that energizing coil L C closes the holding switch 14¹, corresponding to the holding switch 14 in connection with line 8.

When switches 91 and 93 are closed, coil N is energized and thereby resistances R⁷, R⁸, R⁹, R¹⁰, R¹¹ and R¹² are cut out in properly timed sequence, as will be readily understood.

10 It follows that the car is started upward with properly graduated acceleration by the mere push of button D⁸.

The timing means in connection with switch 97, mentioned above, may be omitted, 15 if desired, and current passed through coil LC practically simultaneously with the energizing of coil B, so that low speed motor A¹ is cut out at once and the car is started directly by the high speed motor.

20 The stopping of the car either by the terminal switches or at an intermediate floor is effected in the same way as described in connection with the installation shown in Fig. 5.

It has been explained how, after the car has 25 started up or down, the operator may cause it to stop automatically at any pre-selected floor, merely by pushing the corresponding button F² or F³, as the case may be. After the selection has thus been made of the floor at 30 which the car will make the next stop, the operator may without stopping, change the selection merely by pushing the proper button, so as to stop at an intermediate floor. For example, upon starting downwardly from the 35 top floor, the button F² may be pushed to set the selecting device so that the car will automatically stop at the second floor. After this selection has been made and while the car is under way, the selecting device may be 40 changed, merely by pushing the button F³, so that the car will stop at the third floor.

Suppose, however, that it is desired to 45 change the selection to a floor beyond the one originally selected. For example, after starting downwardly from the top floor, the operator has pushed the button F³ to stop the car at the third floor and then finds that he does not wish to stop until he reaches the second floor. In order to change the selection in this manner, the coil FC³ must be de-energized to permit the switches 53, 53¹, 55 and 55¹ to open. For this purpose, a push button switch P may be placed in the line 47^b, as shown in Figure 8. As soon as the button P is pushed to open 55 the circuit through line 47^b, the selecting mechanism is reset. The button P may then be released and button F² may then be pushed to set the selecting mechanism to stop the car at the second floor.

60 The floor switches, terminal switches and by passes in lines 13^b and 15^b are duplicated in lines 13^{b1} and 15^{b1}. The by pass switches in lines 41^{b1}, 41^{c1}, 44^{b1} and 44^{c1} are controlled by the same magnetic means, 64 and 65, as 65 controls the corresponding switches in cir-

cuits 41^b etc. However, the floor switches in circuits 13^{b1} and 15^{b1} are opened slightly before those in circuits 13^b and 15^b, either by locating the switches differently or by providing separate cams H¹. The result is that, as 70 a floor is approached at which a stop is to be made, cam H¹ opens the circuit through coil L C first, whereupon switches 91 and 93 are allowed to open, de-energizing the high speed motor, and switches 90 and 92 are 75 allowed to close, energizing the low speed motor. This effects the desirable gradual and accurate stopping of the car.

It will be readily understood that further 80 connections may be provided, if desired, to further control the gradual stopping, as well as the gradual starting of the car, and that an arrangement similar to that shown in Fig. 8 for multi-speed motors may be applied with 85 obvious variations to the installations shown in any of the other figures.

For simplicity in disclosure, single phase electro-magnets have been indicated in the diagrams, but those skilled in the art will readily understand that polyphase magnets 90 may be used instead of the single phase magnets, with obvious modifications in the installation.

While I have shown several definite diagrams of connections embodying my invention, 95 it will be understood that I have not attempted to show all possible embodiments of the invention, and that other obvious arrangements of the controlling devices, within the scope of the appended claims, are comprehended within the scope of my invention.

What I claim is:

1. An elevator installation comprising a car, an electric motor, a control system for the motor including a starting switch, means actuated by the starting operation of the switch to continue the energizing of the motor, after the switch has been returned to neutral position, until the car has reached a pre-selected floor, and means independent of the starting switch and operable at any time, at the will of the operator, to cut out the floor first selected and to select another floor, without stopping the motor.

2. In an elevator installation comprising an electric motor, electro-magnetic means for controlling the current to the motor, a starting switch for energizing said means, a holding switch actuated by said means for maintaining current through said means independently of the starting switch, an automatically operated floor switch for interrupting the current through said means at each floor, a by-pass for a floor switch, a normally closed switch in the by-pass, and means under the control of the operator for opening said by-pass switch.

3. In an elevator installation comprising an electric motor, electro-magnetic means for controlling the current to the motor, a start-

- ing switch for energizing said means, a holding switch actuated by said means for maintaining current through said means independently of the starting switch, an automatically operated floor switch for interrupting the current from said means at each floor, a by-pass for a floor switch, a normally closed switch in the by-pass, electro-magnetic means for opening the by-pass switch, and means under control of the operator for energizing the last said electro-magnetic means. 10
4. In an elevator installation comprising an electric motor, electro-magnetic means for controlling the current to the motor, a starting switch for energizing said means, a holding switch actuated by said means for maintaining current through said means independently of the starting switch, an automatically operated floor switch for interrupting the current from said means at each floor, a by-pass for a floor switch, a normally closed switch in the by-pass, electro-magnetic means for opening the by-pass switch, a switch under control of the operator for energizing the last said electro-magnetic means, a by-pass around the last said switch, a normally open holding switch in said by-pass, and connections whereby the energizing of the last said magnetic means closes the last said holding switch. 30
5. In an elevator installation comprising an electric motor, electro-magnetic means for controlling the current to the motor, a starting switch for energizing said means, a holding switch actuated by said means for maintaining current through said means independently of the starting switch, an automatically operated floor switch for interrupting the current from said means at each floor, a by-pass for a floor switch, a normally closed switch in the by-pass, electro-magnetic means for opening the by-pass switch, a switch under control of the operator for energizing the last said electro-magnetic means, a by-pass around the last said switch, a normally open holding switch in said by-pass, and connections whereby the energizing of the last said magnetic means closes the last said holding switch, the circuit of the last said electro-magnetic means being connected to the circuit through the motor so that stopping of the motor releases said magnetic means. 40
6. In an elevator installation comprising an electric motor, an electro-magnetic means for controlling the current through the motor, a circuit independent of the motor circuit for energizing the electro-magnetic means, a starting switch in the circuit of the electro-magnetic means, a by-pass around the starting switch, a normally open holding switch in the by-pass, connections whereby energizing of the electro-magnetic means closes the holding switch, floor switches for each intermediate floor interposed in the circuit of the electro-magnetic means, said floor
- switches being normally closed, automatic means for opening each of said switches when the car reaches the respective floor, a by-pass around the floor switch, a normally closed switch in the by-pass, and means under control of the operator for opening the last said switch. 70
7. In an elevator installation comprising an electric motor, an electro-magnetic means for controlling the current through the motor, a circuit independent of the motor circuit for energizing the electro-magnetic means, a starting switch in the circuit of the electromagnetic means, a by-pass around the starting switch, a normally open holding switch in the by-pass, connections whereby energizing of the electro-magnetic means closes the holding switch, floor switches for each intermediate floor interposed in the circuit of the electro-magnetic means, said floor switches being normally closed, automatic means for opening each of said switches when the car reaches the respective floor, a by-pass around the floor switch, a normally closed switch in the by-pass, and means under control of the operator for opening the last said switch, the last said means comprising electro-magnetic means for opening the switch, a circuit connected to the power circuit of the motor for energizing the last said electro-magnetic means, a normally open switch in the last said circuit closable at the will of the operator, a by-pass around the last said switch, and a normally open holding switch in the by-pass closable upon the energizing of the last said electro-magnetic means. 80
8. An installation in accordance with claim 7, and having a separate by-pass around the floor switch of each intermediate floor, and separate means for controlling the several switches in these several by-passes. 105
9. An elevator installation comprising a plurality of motor windings of different speed, means operable to automatically control successive operation of the motor windings for stopping the car, means normally by-passing said controlling means, a starting switch, and a switch in the car independent of the starting switch for opening said by-passing means. 110
10. In an elevator installation comprising a plurality of motors, a control circuit for each motor, a normally closed switch in each circuit, automatic means for opening said switches in succession as the car approaches a predetermined point in its travel, a by-pass around each of said switches, a normally closed switch in each by-pass, and common means within the control of the operator for opening corresponding by-pass switches in each of said circuits. 120
11. An elevator installation comprising a motor, a control circuit for the motor including a starting switch and a normally closed

- automatically operable stopping switch, a by-pass around said starting switch, a magnetic coil common to the main control circuit and the circuit through said by-pass, a switch in said by-pass and held closed by said coil when the latter is energized, but adapted to open when the coil is de-energized, a by-pass around said stopping switch, and a switch in the last mentioned by-pass, which is normally closed so as to render the automatically operable switch ineffective to stop the motor, but adapted to be manually opened to render the same effective.
12. An elevator installation comprising a motor, a control circuit therefor including a starting switch and a normally closed automatically operable stopping switch for opening the circuit through the motor at a predetermined point in its operation, a by-pass around said stopping switch, a magnetic coil common to the main control circuit and the circuit through said by-pass, a switch in said by-pass which is normally closed so that the stopping switch is ineffective to stop the mo-
- tor, and a magnet under manual control to open the by-pass switch to render said stopping switch ineffective.
13. An elevator installation comprising a motor, a control circuit therefor including a starting switch and a normally closed automatically operable stopping switch for opening the circuit through the motor at a pre-selected point in its operation, a by-pass around said stopping switch, a switch in said by-pass, a magnetic coil for controlling the by-pass switch which is held open when said coil is energized, thereby rendering said automatically operable stopping switch effective to stop the motor after the switch in the by-pass has been opened, and manually controlled means for interrupting the circuit through said coil, thereby permitting the by-pass switch to close and rendering the stopping switch ineffective.
- In testimony whereof I have hereunto signed my name to this specification.

ERNEST B. THURSTON.

CERTIFICATE OF CORRECTION.

Patent No. 1,714,285.

Granted May 21, 1929, to

ERNEST B. THURSTON.

It is hereby certified that error appears in the printed specification of the above numbered patent requiring correction as follows: Page 8, line 27, claim 12, for the word "ineffective" read "effective"; and that the said Letters Patent should be read with this correction therein that the same may conform to the record of the case in the Patent Office.

Signed and sealed this 30th day of July, A. D. 1929.

(Seal)

M. J. Moore,
Acting Commissioner of Patents.
